UNITED STATES PATENT OFFICE

121,077

DESIGN FOR A BUFFET HOLDER FOR SILVERWARE OR ANALOGOUS ARTICLE

John S. O'Connell, Newburyport, Mass., assignor to Towle Manufacturing Company, Newburyport, Mass., a corporation of Massachusetts

Application March 19, 1940, Serial No. 91,070

Term of patent 14 years

To all whom it may concern:

Be it known that I, John S. O'Connell, a citizen of the United States residing at Newburyport, in the county of Essex and Commonwealth of Massachusetts, have invented a new, original, and ornamental Design for a Buffet Holder for Silverware or Analogous Article, of which the following is a specification, reference being had to the accompanying drawings, forming a part thereof.

In the accompanying drawings, Figure 1 is a plan view of a buffet holder for silverware or analogous article showing my new design;

Fig. 2 is a front elevational view;

Fig. 3 is a side elevational view;

Fig. 4 is a section on the line 4—4 of Fig. 1 looking in the direction of the arrows, showing the lowest depressed portion of my buffet holder; and

Fig. 5 is a section on the line 5—5 of Fig. 1 looking in the direction of the arrows.

I claim:

The ornamental design for a buffet holder for silverware or analogous article, substantially as shown.

JOHN S. O'CONNELL.
